(57) **CLAIM**

The ornamental design for the telecommunications device clip and belt holder, as shown and described.

DESCRIPTION

FIG. 1 is a perspective of the clip portion of the telecommunications device clip and belt holder from a first perspective angle;

FIG. 2 is a perspective of the clip portion of the telecommunications device clip and belt holder from a second perspective angle;

FIG. 3 is a front elevational view of the clip portion of the telecommunications device clip and belt holder shown in FIG. 1;

FIG. 4 is a rear elevational view of the clip portion of the telecommunications device clip and belt holder shown in FIG. 1;

FIG. 5 is a right side elevational view of the clip portion of the telecommunications device clip and belt holder shown in FIG. 1;

FIG. 6 is a left side elevational view of the clip portion of the telecommunications device clip and belt holder shown in FIG. 1;

FIG. 7 is a top plan view of the clip portion of the telecommunications device clip and belt holder shown in FIG. 1;

FIG. 8 is a bottom plan view of the clip portion of the telecommunications device clip and belt holder shown in FIG. 1;

FIG. 9 is a perspective of the belt holder portion of the telecommunications device clip and belt holder from a first perspective angle;

FIG. 10 is a perspective of the belt holder portion of the telecommunications device clip and belt holder from a second perspective angle;

FIG. 11 is a front elevational view of the belt holder portion of the telecommunications device clip and belt holder shown in FIG. 9;

FIG. 12 is a rear elevational view of the belt holder portion of the telecommunications device clip and belt holder shown in FIG. 9;

FIG. 13 is a right side elevational view of the belt holder portion of the telecommunications device clip and belt holder shown in FIG. 9;

FIG. 14 is a left side elevational view of the belt holder portion of the telecommunications device clip and belt holder shown in FIG. 9;

FIG. 15 is a top plan view of the belt holder portion of the telecommunications device clip and belt holder shown in FIG. 9; and,

FIG. 16 is a bottom plan view of the belt holder portion of the telecommunications device clip and belt holder shown in FIG. 9.
